(57) **CLAIM**

The ornamental design for a putting marker, as shown and described.

DESCRIPTION

FIG. 1 is a perspective view of a putting marker; FIG. 2 is a front view thereof, wherein a rear view, a top view, and a bottom view are mirror images of the front view; and, FIG. 3 is a left-hand side view thereof, wherein a right-hand side view is a mirror image of the left-hand side view.
